Specification for Design.

Patented Sept. 22, 1914.

Application filed July 3, 1914. Serial No. 848,959. Term of patent 14 years.

To all whom it may concern:

Be it known that I, JULES J. SARRAZIN, a citizen of the United States, residing at New Orleans, in the parish of Orleans and State of Louisiana, have invented a new, original, and ornamental Design for Tooth-Brushes, of which the following is a specification, reference being had to the accompanying drawing, forming a part thereof, in which—

I claim:

The ornamental design for a tooth brush, as shown.

In testimony whereof I affix my signature, in the presence of two witnesses.

JULES J. SARRAZIN.

Witnesses:

M. J. HOWARD,
